UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

AIR GUN.

Application filed September 21, 1925. Serial No. 57,686.

The invention relates to air guns of the repeating type having a magazine for holding the shot and a feed mechanism for introducing the same into the barrel. In guns 5 of this type it is common to provide a detachable barrel within the outer casing or magazine, the latter having a loading aperture therein which is closed by a member carried by said barrel. When the barrel is 10 threadedly secured to said casing and is screwed tightly against the cooperating member it sometimes happens that the closure is not in exact alignment with the loading aperture, thus permitting the shot in 15 the magazine to fall out of the gun. While this trouble may be remedied by slightly unscrewing the barrel until the closure registers with the magazine aperture it is not always understood by the children using the 20 gun, thus causing annoyance and dissatisfaction.

One of the objects of my invention is to provide an arrangement for overcoming the defect above referred to and this has been 25 accomplished by securing the barrel to the gun in such a manner as to permit unlimited rotation of the barrel without axial movement after it has been secured in axial position by threaded engagement. Another 30 object is to provide an improved construction of abutment for receiving the inner end of the barrel and securing the same to the outer casing.

In the drawings:

- 35 Figure 1 is a side elevation of an air gun;
- Figure 2 is a longitudinal section through a portion of the gun barrel;
- Figure 3 is an enlarged view illustrating the engagement of barrel and abutment;
- 40 Figure 4 is a sectional view of the abutment;
- Figure 5 is an end view thereof.

A represents the air gun as a whole provided with the usual operating mechanism 45 for propelling the shot, this mechanism not being specifically illustrated since it forms no part of the present invention. B is the outer casing or so-called false barrel which forms the magazine C for the shot and is 50 provided at its outer and upper portion with a loading aperture D. E is the inner tube or true barrel extending within the outer casing and having at its outer end the clo-

sure F adapted to engage the outer casing to close the magazine. The inner end of the 55 barrel E has secured thereto a member G having external threads H, an annular flange I and a cut-away portion J intermediate the threads and said flange. K is a feeding mechanism for introducing the shot 60 one at a time into the barrel E through the aperture L.

For engaging the threaded end of the barrel E there is provided an abutment comprising a sheet metal tube M preferably 65 formed from a flat sheet and provided with a longitudinal slot N between the adjacent edges. The tube is permanently secured within the outer casing B by spot-welding or other suitable means and is provided at 70 its forward end with a nut O having a cylindrical outer surface P sleeved within said tube and having an annular flange Q engaging the end of said tube. The flange has two or more apertures R therein for receiving 75 the ears S which project from the tube M, the latter being bent inward as indicated at T to secure the nut to the tube. The nut O is provided with a threaded aperture U adapted to engage the threads H and 80 is also provided with the enlarged recess V for receiving the threads H when the barrel is threaded through the aperture U.

With this construction, the barrel E is secured to outer casing by the threaded engagement of portions H and U, thus drawing the closure F into engagement with the outer casing. Further rotation of the barrel E allows the threaded portion H to engage in the enlarged recess V and the threaded 90 portion U to engage in the cut-away portion J, thus permitting relative rotation of the parts without further axial movement. The flanges I and Q prevent further axial movement inward while the threaded portions H 95 and U prevent axial movement outward without corresponding rotation.

The closure member F has secured thereto, the spring arm W having a detent X for engaging and closing the loading aperture 100 D when the aperture L is in its upper position. It will be readily apparent therefore, that the threading of the barrel E into engagement with the abutment draws the detent X into longitudinal alignment with the 105 aperture D, while the radial registration

will be obtained by further rotation of the barrel without corresponding axial movement.

What I claim as my invention is:—

- 5 1. In a gun, the combination with a tubular outer casing simulating a barrel and formed with a loading aperture, of an abutment secured within said casing, formed with a threaded opening, a tube within said 10 casing forming the true barrel for said gun and having a threaded portion adapted to be screwed into and past the threads of said opening; a closure for said loading aperture carried by said tube, said closure 15 being registered with the plane of the loading aperture transverse to the barrel by threading the barrel through said opening of the abutment, said tube being freely rotatable relative to the abutment when its 20 threads having been screwed past those of the abutment to engage said closure with said loading aperture.
2. In a gun, the combination with an outer tubular casing simulating a barrel and 25 formed with a loading aperture, of an abutment within said barrel having an aperture therethrough, a tube within said barrel having an end portion retained in said opening and rotatable within the barrel in a 30 fixed longitudinal relation to the barrel, and a closure mounted upon said tube and engageable with and disengageable from said loading aperture by rotation of the tube.
3. In a gun, the combination with an outer 35 casing, of a removable barrel within said casing forming therebetween a magazine and having a threaded inner end, a threaded abutment on said casing for engaging said threaded end, one of said threaded members 40 having a cutaway portion adapted to engage the threaded portion of the other member to permit relative rotation of said members without axial movement, and cooperating abutments on the respective threaded members for limiting axial movement in one direction.
4. In a gun, the combination with a tubular casing simulating a barrel, provided with 45 a threaded abutment therein, said casing forming a magazine and having a loading aperture therein, a tube within said casing forming the true barrel for said gun and having a threaded portion for engaging said threaded abutment, a closure for the end of 55 said casing secured to said tube, means carried by said tube for closing said loading aperture, and a cut-away portion on one of said threaded members adapted to engage the threaded portion of the other member 60 after a predetermined threaded engagement

of said members whereby said tube and closing means may be rotated without axial movement.

5. In a gun, the combination with a tubular casing simulating a barrel provided with 65 a threaded abutment therein, said casing forming a magazine having a loading aperture therein, a tube within said casing forming the true barrel and having a threaded portion for engaging said threaded abutment, a closure for the end of said tubular casing secured to said inner tube, a spring 70 detent carried by said closure adapted to engage said loading aperture when said tube is axially and rotatably aligned therewith, cut-away portions on said tube and said abutment arranged adjacent to the respective threaded portions thereof, each of said cut-away portions being adapted to receive the threaded portion of the other member after 75 a predetermined threaded engagement thereof to permit rotation of said tube without axial movement thereof, and cooperating surfaces on said tube and abutment for limiting axial movement in one direction. 80

6. In a gun, the combination with a tubular casing simulating a barrel and a tube within the same forming the true barrel, of an abutment for engaging said tube comprising a sheet metal tube secured within said 90 casing, an annular member adapted to be removably secured to said inner tube having a cylindrical portion engaging the inner surface of said sheet metal tube, and an annular flange engaging the end of the same, said 95 annular flange having a recess therein, and an ear projecting from said sheet metal tube into said recess and bent into engagement with the outer face of said nut.

7. In a gun, the combination with a tubular casing simulating a barrel, and a tube within the same forming a true barrel and provided with a threaded end, of an abutment for receiving said inner tube comprising a longitudinally split sheet metal tube 105 secured within said tubular casing, an annular nut interiorly threaded to engage said threaded end having a cylindrical portion within said sheet metal tube and an annular flange engaging the end of the same, said 110 annular flange being provided with a pair of recesses having the bottom portions thereof flush with said cylindrical portion, and a pair of integral ears projecting from said sheet metal tube through said recesses and 115 bent into engagement with the outer face of said nut.

In testimony whereof I affix my signature.

CHARLES F. LEFEVER.
